COMBINED FOLDING CHAIR AND TACKLE BOX

Albert Sokolis, 302 Bens Drive, Chatham, Ill.

Filed Apr. 26, 1963, Ser. No. 74,632

Term of patent 14 years

(Cl. D15—1)

FIG. 1.

FIGURE 1 is a perspective view from the front of a combined folding chair and tackle box showing my new design, the back rest being in extended position, side opposite to that shown being the same, and

I claim:

The ornamental design for a combined folding chair and tackle box, as shown and described.
